EXTENSIBLE CONSOLE TABLE

Anthony Marino, Somerville, Mass.

Application March 2, 1938, Serial No. 193,525

4 Claims. (Cl. 311—42)

This invention relates to a console table which is so constructed as to permit enlargement thereof and interposition of leaves therein to provide an extension table.

So far as I am aware, console tables have never heretofore been constructed for extension. The table of my invention is adapted for use in any one of a variety of positions, including the usual double leaf flat top position; a position with one leaf extended upwardly and supported against a wall; open contracted position; and extended position, either with one or more interposed leaves.

The mechanical features of my construction permit incorporation of bracing and reinforcement adequate to insure a sturdy table in all positions, including extended position, and, as will be hereinafter described, additionally permit incorporation of an extra leg which is adapted to support the central portion of the table when the table is in extended position, yet which does not detract from the appearance of the table in contracted or console position.

My table is designed to meet the customers' demand for small tables which on occasions may be enlarged to provide extra table surface for dining or other purposes. Its advantages will be plainly apparent from the description given herein, when taken together with the drawings, in which,

Fig. 1 is a plan of the table in open contracted position;

Fig. 2 is a front elevation of the table with one leaf extended upwardly into a vertical position where it can be supported against a wall;

Fig. 3 is a plan of the table in extended position, showing the interposition of leaves;

Fig. 4 is a partial enlarged rear elevation of the table with the leaves in a double flat top position;

Fig. 5 is an enlarged detail of the arrangement of one of the hinges shown in Fig. 4;

Fig. 6 is a cross-section taken along the lines 6—6 of Fig. 5; and Fig. 7 is a fragmentary plan of one of the hinge constructions, illustrating the leaves in a partially extended relation.

As will be readily understood from the drawings, my table is adapted for use in four positions, including the position illustrated by Fig. 4, wherein one leaf 10 is folded over into a position on top of and substantially co-extensive with, another leaf 12; the position shown in Fig. 2, wherein the top leaf 10 has been hinged upwardly into a position where it can be supported against a wall; the position illustrated

in Fig. 1, wherein the top leaf 10 has been folded downwardly into the plane of the bottom leaf 12 to provide a flat top table; and the position shown in Fig. 3, wherein the leaves 10 and 12 have been separated and additional leaves 14 have been inserted therebetween.

In order to support the top leaf 10, when it is in the unfolded horizontal positions illustrated in Figs. 1 and 3, one of the legs is adapted to be hinged on a vertical axis outwardly under the leaf 10, as illustrated in dotted lines in Figs. 1 and 3.

To describe the construction more in detail, the leaf 12 is fixedly secured to two of the table legs 20 and 22. The other leaf 10, as illustrated in Figs. 3 and 4, is hingedly secured to a frame 30, supported by legs 32 and 34, and is adapted for movement about a horizontal axis, as will be described more fully hereinafter. The leg 34 is hingedly connected to the frame 30 by an arm 36, which has a hinged connection at 38 with the frame 30, and is adapted to be swung outwardly, as illustrated in dotted lines in Figs. 1 and 3.

The table thus comprises essentially two separate sections, A and B, each section comprising one leaf and a pair of legs.

These two sections are connected together by a common slide extension arrangement 40, shown in dotted lines in extended position in Fig. 3, and in contracted position in Fig. 1. The end members at one end of this slide extension device 40 are fixedly secured to the underside of leaf 12, and the other end members of the slide extension device 40 are secured to the inner side of the frame 30, and are suitably braced by horizontal angle frames 42, and vertical frames 43, and the end members are so positioned relative to leaf 12, that, in contracted position of the slides, the inner edges of leaves 10 and 12 will abut as illustrated in Fig. 1.

Preferably, each central slide 40a is fixedly secured to a plate member 44, to which is fixedly attached a central leg 46 with suitable bracing 47. The frame 30 is provided with a cut-out portion 48 to accommodate the top of leg 46 when the table is in the position shown in Fig. 1. As will be seen, the leg 46, in the position shown in Fig. 3, serves as a support for the central portion of the table. While the leg 46 adds greatly to the strength of the table in extended position, it can be omitted, the extension slides being of such a nature that they are self-supporting even in extended position.

In order to permit separation of the sections

A and B, leaf 10 is hinged, not to leaf 12, but to the frame 30, as shown in Fig. 4, through the provision of blocks 50, fixedly secured, one at each end of the frame 30, to the upper surface of frame 30, as shown more in detail in Figs. 5 and 6. The leaf 10 is hinged to these blocks 50, the hinges being of such construction that when the top leaf 10 is in the position shown in Fig. 4, the leaf 10 is spaced above the block 10 and above the remaining top surface of frame 30 a distance sufficient to permit leaf 12 to be interposed therebetween. In addition, in order to permit the edge of the leaf 12 to be flush with the rear edge of leaf 10, the under surface of leaf 12 adjacent each outer edge of the leaf is recessed at 52, to accommodate the blocks 50 when sections A and B are in the position shown in Fig. 4. As illustrated more in detail in Fig. 6, the rear edge of the table provides a flush surface, with the exception of the protruding hinge portions.

Preferably my hinges take the form illustrated in Figs. 5, 6 and 7, and comprise two members having U-shaped portions 53, countersunk and secured one in leaf 10 and the other in block 50. The two hinge members are connected together by a series of bars 54 having a pivot pin 56 passing through their central portions. The hinge shown has six bars, each bar having a short arm and a long arm. As shown in Fig. 5, one bar has a lower short arm pivoted upon a pin 59, which is fixedly secured across the lower U-shaped portion 53, and a longer upper arm which is pivoted upon a pin 60, which is slidable in channels 62, formed in the walls of the upper U-shaped portion 53. Each alternate bar is similarly fastened, while the intermediate bars are reversed, so that the lower arm is the long arm and is pivoted to a pin 60, slidable in portion 53 of the lower hinge member, and the upper arm is the short arm, and is pivoted to a pin 58 fixed across the U-shaped portion of the upper member.

The two U-shaped portions 53 are so positioned relative to the block 50 and leaf 10 that when the leaf 10 is in the horizontal position illustrated in Figs. 4, 5 and 6, the pin 56 is in a horizontal plane with the contacting surfaces of leaves 10 and 12. As top leaf 10 is hinged 180° to the position illustrated in Fig. 7, the pins 60 slide divergently inwardly relative to the rear edges of leaf 10 and block 50 in channels 62, and pins 58 and 59 come to rest in a single horizontal plane, with pin 56 in a vertical plane with the end surface of block 50 and contacting end surface of leaf 10, thus causing the leaves 10 and 12 to be flush against each other, as shown in Fig. 1.

In this position, the leg 34 is hinged away from frame 38, to provide support for the horizontally disposed hinged leaf 10.

From the position shown in Fig. 1, it is obvious that sections A and B may be separated, the leaf 12 of section B sliding off the blocks 50 as indicated by Fig. 7, finally reaching, if desired, the position shown in Fig. 3, leaving the central support 44 and leg 46 substantially central of the table. Separate leaves may then be interposed on the extension slides 40, it being understood that the leaf which is interposed adjacent the leaf 10 has recesses on its under surface substantially identical with the recesses 52, described in connection with leaf 12, so that the leaf will set down over the blocks 50 to abut the edge of the leaf 10.

Other forms of hinges, particularly double link hinges, which permit 180° movement of leaf 10

relative to block 50, while permitting, as with my illustrated form of hinge, the edge of leaf 10 to abut closely the rear edge of block 50 when the 180° pivoting has occurred, may obviously be used.

However, many of such hinges are apt to require a cutting away of the top surface of the table, thus exposing a portion of the hinge on top of the table when the leaves are in the open position of Figs. 1 and 3, although such hinges may obviate the necessity of blocks 50 and undercut recesses 52.

In other words, while I have illustrated my preferred form of hinge, it is obvious that any form of hinge which will permit the interposition of leaf 12 between the anchorage points of each hinge, and which will allow 180° movement to bring the rear edges of the two leaves in abutting engagement, will be satisfactory for the purposes of my extension table. In addition, the hinge leg 34 must be so attached to the table that it will permit a fastening of the hinge to the support 30 without interfering with the outward movement of the swinging leg, to provide support for the leaf 10. However, if the swinging leg is not provided, some equivalent means for supporting the leaf 10 may be utilized.

I claim:

1. A console table of the type described, comprising two independent sections, one of said sections including a table leaf supported in a fixed horizontal position, the other of said sections including a supporting frame and a table leaf hinged to said frame for movement about a horizontal axis from a position folded on top of said fixed leaf 180° to a position abutting and in the plane of the fixed leaf, means associated with said frame for supporting said hinged leaf in said hinged position, and extensible slide means connecting said sections, whereby said sections may be moved to relatively remote positions to permit interposition of an additional leaf intermediate said fixed and said hinged leaves.

2. A console table of the type described, comprising a front and back section, said front section including a table leaf fixedly supported in a horizontal position, said back section including a supporting frame and a table leaf hinged to said frame for movement about a horizontal axis from a position folded over and substantially co-extensive with said fixed leaf 180° to a position abutting and in the plane of said fixed leaf, means associated with said back section for supporting said hinged leaf in said hinged position and means extensibly connecting said sections together, including a series of expandable slides, and a leg fixedly secured to a central slide, whereby said sections may be moved to positions relatively remote from each other and from said leg, to permit interposition of an additional leaf intermediate said fixed leaf and said hinged leaf.

3. A console table of the type described, comprising two independent sections, each section including a plurality of legs and a table leaf, the leaf of one of said sections being flexibly secured to its legs in a horizontal position, the leaf of the other section being hingedly secured to a frame supported by its legs for movement about a horizontal axis from a position folded over and substantially co-extensive with said fixed leaf 180° to a position abutting and in the plane of said fixed leaf, one of the legs of said section being hingedly secured to said frame for movement about a vertical axis to a position supporting said hinged leaf in said hinged position, and means

extensibly connecting said sections together, whereby said sections may be moved to relatively remote positions, to permit interposition of an additional leaf intermediate said fixed leaf and said hinged leaf.

5 4. A console table of the type described comprising two independent sections, one of said sections including a plurality of legs and a table leaf fixedly secured to said legs in a horizontal position, the other of said sections including at least one leg, a frame supported thereby, and a table leaf hinged to said frame for movement about an

horizontal axis from a position folded over and substantially co-extensive with said fixed leaf 180° to a position abutting and in the plane of said fixed leaf, means associated with said frame for supporting said hinged leaf in said hinged position, and means extensibly connecting said sections together, whereby said sections may be moved to relatively remote positions to permit interposition of an additional leaf intermediate said fixed leaf and said hinged leaf.
